UNITED STATES PATENT OFFICE.

EDGAR M. SMITH, OF CHICAGO, ILLINOIS.

REINFORCED RAIL-JOINT.

1,086,734.

Specification of Letters Patent. Patented Feb. 10, 1914.

Application filed October 7, 1912. Serial No. 724,300.

To all whom it may concern:

Be it known that I, EDGAR M. SMITH, a citizen of the United States, residing at Chicago, county of Cook, State of Illinois, 5 have invented a certain new and useful Improvement in Reinforced Rail-Joints, and declare the following to be a full, clear, and exact description of the same, such as will enable others skilled in the art to which it 10 pertains to make and use the same, reference being had to the accompanying drawings, which form a part of this specification.

My invention has for its object to produce a simple and strong rail joint.

15 A further object of my invention is to produce a reinforcing device for splice bars so as greatly to increase the strength of a joint containing the same.

A further object of my invention is to 20 produce an efficient reinforcing means for splice bars now in use.

The various features of novelty whereby my invention is characterized will herein-after be pointed out with particularity in 25 the claims; but for a full understanding of my invention and of its objects and advantages, reference may be had to the following detailed description taken in connection with the accompanying drawings, 30 wherein:

Figure 1 is a side elevation of a joint arranged in accordance with the preferred form of my invention; Fig. 2 is a view similar to Fig. 1, showing the opposite side of 35 the joint; Fig. 3 is a transverse section taken at the right hand side of the center of the joint, as viewed in Fig. 1, and looking toward the left of Fig. 1; Fig. 4 is a central longitudinal section through the joint with 40 the rail ends removed; and Figs. 5 and 6 are bottom plan views of the reinforcing members.

In the drawings I have illustrated only a single preferred embodiment of my invention 45 used in connection with a common form of splice bar; but, while I consider the specific arrangement illustrated as being probably the best form of my invention, and while I shall, for the sake of brevity, de- 50 scribe only this single form in detail, I do not desire to be limited to any particular construction and arrangement except as pointed out in the definitions of my invention which constitute the appended claims.

55 Referring now to the drawings, 1 and 2 represent two meeting rail ends joined together by suitable splice bars, 3 and 4. The

splice bars are of the type having an upper chord or body portion enlarged at the top as indicated at 5 and provided at the bottom 60 with a foot flange, 6; the enlargements fitting under the heads of the rail ends and the foot flanges overlying and resting upon the rail bases. The enlargement extends upon both sides of the body portion so as to provide each splice bar with an outwardly-projecting rib or head, 7 along the upper edge. The splice bars are fastened to the rails by means of the usual bolts, 8.

In accordance with my invention I add to the old structure heretofore described a reinforcing device which will add greatly to the strength of the joint. To this end I have provided auxiliary splice bars, 9 and 10 each consisting of an upper chord 11 and a foot flange 12. The parts are so proportioned that the foot flange of each auxiliary splice bar overlies and fits upon the foot flange of the corresponding main bar, while the upper chord of each auxiliary splice bar fits 80 against the outer face of the corresponding main splice bar and engages with the under side of the corresponding rib or head, 7. The auxiliary splice bars need not be as long as the main bars since the need for reinforcement is greatest at the point where the two rail ends meet, and I have therefore illustrated the auxiliary splice bars as being simply long enough to extend well beyond the two middle bolt holes of the joint; the auxiliary splice bars being held in place by means of the two intermediate fastening bolts, 8, which pass through registering holes in the four bars and in the webs of the rails. In order to secure both lightness and 90 strength, the main portion of each auxiliary splice bar may be made relatively thin, an outwardly-projecting strengthening bead or rib 13 may be placed along the top and ends, and a comparatively wide stiffening rib 14 95 may be placed just at the center so as to lie at right angles to the longitudinal axis of the rails.

It will be seen that by fitting the auxiliary splice bars beneath the heads or ribs on the main bars, the downward pressure on the main bars is carried directly to the upper edges of the auxiliary bars independently of the bolts and without leaving an idle zone at any point in the auxiliary bars. Furthermore the outwardly-projecting ribs or heads serve to guard and protect the upper edges of the auxiliary bars. For the purpose of obtaining still further strength

and transmitting some of the load on the rails directly to the auxiliary splice bars, I have provided the latter with inwardly-projecting flange members which extend beneath and in engagement with the rail bases, each flange preferably extending substantially from one side of the rails to the other. In the particular arrangement shown, the member 10 has a wide inwardly-extending flange, 15, which is long enough to extend entirely across the under side of the rails, this flange having a recess in its upper face into which extends a narrower flange or tongue 16 forming part of the member 9. The parts are so proportioned that when the elements of the joint are assembled, the upper faces of the members 15 and 16 lie in the same horizontal plane and engage with the under side of the rail bases. By interlocking the members 15 and 16, relative displacement lengthwise of the rails is prevented, while at the same time relative transverse adjustment is afforded in order to permit wear to be taken up or enable the splice bars to be fitted to rails varying somewhat in size. The transverse adjustment has no effect upon the elevation of the upper faces of the flange members 15 and 16, these faces remaining at all times in engagement with the rails.

The flange member 15 may conveniently be made up of two separated arms, 17 and 18 projecting inwardly from the lower edge of the member 10 and connected together at their free ends by a depressed crosspiece lying below the upper face of the member 15 a distance somewhat greater than the thickness of the tongue or flange 16 so that the latter may be slid freely in place between the arms 17 and 18. I also prefer to incline the inner edges or faces of the arms 17 and 18, as indicated at 20, and to cut away the lower corners at the sides of the member 16 at angles corresponding to the inclination of the faces 20, as indicated at 21, so that as long as the rails are resting upon the member 16 the pressure will be transmitted to the member 15.

I claim:

1. A splice bar device comprising body portions adapted to lie beside the meeting ends of two rails, tongues or flanges extending inwardly from the lower ends of the body portions and adapted to underlie the bases of the rails, said tongues or flanges being interlocked so as to prevent relative movements in the direction of the length of the rails and permit relative movements in a transverse direction without varying the relative positions of their upper faces with respect to the plane of the rail bases, and shoulders on one of said tongues or flanges engaging with the under side of the other

tongue or flange, to transmit a downward thrust on the latter tongue or flange to the other.

2. A splice bar device for rail joints comprising two members each having a body portion adapted to lie at one side of the meeting ends of two rails, one of said members having at its lower edge a flange extending inwardly so as to underlie the bases of the rails, said flange having a recess in the top thereof, and the other of said members having an inwardly extending part adapted to lie within said recess, and a cross piece on said flange underlying the bottom of said part.

3. A splice bar device for rail joints comprising two members each of which has a body portion adapted to lie beside the meeting ends of two rails, one of said members having at its lower edge an inwardly projecting flange adapted to underlie and engage with the bases of the rails, said flange having a recess extending through its upper face in a transverse direction, and the other member having an inwardly projecting part adapted to fit within said recess and underlie and engage with the bases of the rails, said flange having shoulders underlying said part and adapted to transmit a downward thrust on said part to said flange.

4. A splice bar device for rail joints comprising two members each of which has a body portion adapted to lie beside the meeting ends of two rails, one of said members having at its lower edge an inwardly projecting flange adapted to underlie and engage with the bases of the rails, said flange having a recess extending through its upper face in a transverse direction, and the other member having an inwardly projecting part adapted to fit within said recess and underlie and engage with the bases of the rails, the side walls of said recess and the adjacent corners of the part lying therein being inclined.

5. A splice bar device for rail joints comprising two main bars, auxiliary bars lying outside of and beside the main bars, one of said auxiliary bars having an inwardly projecting flange at its lower edge adapted to underlie and engage with the bases of the rails to which the device is applied, said flange having in its upper face a recess extending transversely of the rails, and the other auxiliary bar having an inwardly extending part fitting into said recess.

In testimony whereof, I sign this specification in the presence of two witnesses.

EDGAR M. SMITH.
